UNITED STATES PATENT OFFICE.

CHARLES GULLOTTI, OF PHILADELPHIA, PENNSYLVANIA.

DISPLAY-FORM.

1,175,748.

Specification of Letters Patent.

Patented Mar. 14, 1916.

Application filed July 10, 1914. Serial No. 850,197.

To all whom it may concern:

Be it known that I, CHARLES GULLOTTI, a citizen of Italy, residing at Philadelphia, in the county of Philadelphia and State 5 of Pennsylvania, have invented new and useful Improvements in Display-Forms, of which the following is a specification.

This invention relates to display forms and the principal object of the invention is 10 to provide a waist and skirt form which may be combined or connected together in a simple manner to produce a complete dress form and each of which is adapted to be adjustably mounted, separately, upon 15 independent standards.

Further objects of the invention will appear as the following description is read in connection with the accompanying drawing, which forms a part of this application, 20 and in which:—

Figure 1 is a side elevation of the complete dress form with parts broken away. Fig. 2 is a perspective view of the waist form with parts broken away. Fig. 3 is 25 a perspective view of the skirt form with parts broken away.

Referring more particularly to the drawing, 1 represents the skirt form and 2 the waist form. The skirt form is preferably 30 constructed of a hollow body covered with some suitable material and having the upper end thereof closed by a plate 3 of any suitable material which is covered by a flanged cap 4. The plate 3 has secured 35 thereto and projecting through the same and through the cap 4 a flanged bolt 5 arranged to pass through a partition plate 6 secured within the hollow waist form 2 and is adapted to receive a nut 7 for holding 40 the parts together as can be plainly seen from an inspection of Fig. 1. The skirt form above the hip portion is tapered into a waist portion which enters into and closely fits the waist portion of the waist 45 form 2, the connection between these parts permitting rotation of the waist form upon the skirt form so that the complete figure may be shown in different positions.

The waist form is constructed in a similar manner to the skirt form and each is 50

provided with horizontal partitions 8 and 9 having the centrally bored bosses 10 and 11 secured thereto for receiving the supporting standards 12 and 13. The standard 12 is adapted to support the entire dress 55 form or the skirt form alone, while the standard 13 is arranged to support the waist form only, and when not in use may have suitable attachments applied thereto for displaying neckwear and like articles, 60 such as is commonly done in department stores. Each boss 10 and 11 is provided with a suitable set screw 14 for engaging their respective standards to hold the forms in adjusted position thereon and each form 65 has suitable apertures 15 and 16 so that access may be had to the set screws.

By employing a device of this character it is not necessary to have as many complete dress, waist or skirt forms as the 70 waist and skirt forms may be combined to produce complete dress forms or may be used independently. When the waist and skirt forms are used to form a complete dress form the joint between the two is almost imperceptible as far as affecting the fit of a gown thereof as the skirt form is 75 slightly enlarged below the joint between the two.

What is claimed is:—

In display apparatus, hollow skirt and waist forms, partitions bridged across said forms and carrying standard receiving means, standards arranged to slidably engage said receiving means, said forms having apertures, means accessible through the apertures for adjustably engaging the standard, said waist form arranged to fit over and be rotatably mounted upon the skirt form, and means for joining the forms together to produce a complete waist form and for holding the parts in adjusted position.

In testimony whereof I affix my signature in presence of two witnesses.

CHARLES GULLOTTI.
